UNITED STATES PATENT OFFICE.

CLIO B. YAW, OF ARLINGTON, NEW JERSEY, ASSIGNOR, BY MESNE ASSIGNMENTS, TO
REMINGTON TYPEWRITER COMPANY, OF ILION, NEW YORK, A CORPORATION OF
NEW YORK.

TYPE-WRITING MACHINE.

1,211,653.

Specification of Letters Patent.

Patented Jan. 9, 1917.

Application filed August 21, 1912. Serial No. 716,147.

To all whom it may concern:

Be it known that I, CLIO B. YAW, citizen of the United States, and resident of Arlington, in the county of Hudson and State of New Jersey, have invented certain new and useful Improvements in Type-Writing Machines, of which the following is a specification.

My present invention relates to means for turning the platen of a typewriting machine either backward or forward at will through a predetermined fractional line space distance so that characters may be printed both above and below the normal line of writing.

The main object of the invention is to provide improved means for the purpose specified.

To the above and other ends my invention consists in the features of construction, combinations of devices and arrangements of parts hereinafter described and particularly pointed out in the claims.

One form of my invention is illustrated in the accompanying drawings, wherein—
Figure 1 is a fragmentary vertical sectional view taken transversely of the platen and platen carriage of a No. 10 Remington typewriting machine embodying my invention. Fig. 2 is a plan view showing the right-hand end portion of said platen and platen carriage. Figs. 3 and 4 are operating views of the fractional line spacing mechanism. Figs. 5, 6, 7 and 8 are detail views of different novel parts.

As appears from Fig. 1, uprights or posts 1 support a top plate 2 in the said Remington No. 10 machine. The carriage is composed of a platen frame 3 detachably and shiftably supported on a rectangular truck 4 comprising front and rear bars 4 and 5 and connecting end bars 6. Said carriage is adapted to travel on roller bearings 7 and provides a support for the usual rotative platen 8, said platen being provided with an axle 9 and being arranged parallel with the front and rear bars 4 and 5 of the truck and near the rear bar, there being a considerable space between the platen and the front bar 4. At the right end of the platen the usual line spacing ratchet wheel 10 is connected thereto, said wheel being adapted to be turned step-by-step by a driving pawl 11 comprised in the regular line spacing mechanism which is mounted on the platen carriage. Said pawl is pivotally mounted at

12 upon an arm 13 adapted to swing concentrically with the axis 9 of the platen. To said pawl is pivotally connected a link or bar 14 whose opposite end is pivotally connected to one arm of a bell crank 15 pivoted at 16 in a lug on the carriage truck. To the other arm of the bell crank 15 is pivotally attached the lower end of a link 17 whose upper end is pivotally connected at 18 to a short crank arm 19 secured by a screw 20 to the rear end of a rock shaft 21 arranged to oscillate in a tubular bearing 22 mounted on the carriage. Said rock shaft extends forward beyond its bearing and is formed with a downwardly projecting hand piece 23 by which the line spacing pawl 11 is operated through the connections hereinbefore described to rotate the platen 8 step-by-step, said platen being adapted to be turned by the pawl 11 either one, two or three notches of the line spacing ratchet wheel 10, according to the adjustment of the usual regulator (not shown). The platen is held against accidental rotation and maintained securely in working position by detent devices which, in the present instance, are controlled by a plurality of keys arranged at the front of the platen carriage where they may be readily manipulated for the purpose of turning the platen either forward or backward at will through fractional line space distances. Said detent devices comprise a roller detent 24 which cooperates with the teeth of the ratchet wheel 10. Said roller detent, as most clearly appears in Fig. 5, is mounted on a spring pressed plunger 25 which slides in a way 26 formed in a block or supporting device 27. The plunger is provided with a screw shank 28 which bears in an opening at the upper end of the block 27. A coiled spring 29 surrounds the shank 28 and presses the plunger and the roller 24 downward. The roller itself is guided in a slot or kerf 30 in the bottom of the block 27. When the roller 24 and the ratchet are separated, as in assembling and disassembling, the head of the shank 28, contacting with the top of the block, prevents displacement of the roller 24 and plunger 25 from the block. The block 27 is rigidly secured to the outer end of an arm 31 that is pivotally mounted on a platen axle 9, the result being that the block is mounted to swing concentrically with the platen. To control the position or

movements of the block, devices are provided comprising an arm 32, the rear end of which is pivotally connected at 32^a with the arm 31 and block 27. The arm 32 extends horizontally forward and is bifurcated at its forward end, providing portions or fingers 33 which are parallel and horizontal, and toothed or provided at their inner opposite faces with rack teeth 34 and 35. The bifurcated forward end of the arm 32 is guided in a vertical slot-way 36 formed in an angular guide bracket 37 that is secured by screws 38 to the front bar 4 of the carriage truck.

Arranged side by side in the slot-way 36 and between the toothed portions 33 are gear members or levers 39 and 40 which are shown detached in Figs. 6 and 7, these members or levers being pivotally supported on a screw pivot 41 which bridges the slot and is held in place by a nut 42. The member 39, which is arranged at the right of and contiguous to the member 40 has a circular head provided at its upper surface with a series of gear teeth 43 which mesh with the rack teeth 34; while the member 40 has a similar circular head provided at its lower side with gear teeth 44 which mesh with the rack teeth 35. The member or lever 39 is provided with a forward extension or arm 45 which terminates in a key or finger button 46, while the member or lever 40 has a forward extension or arm 47 provided with a key 48. Coöperative with the under side of the extensions 45 and 47 is the head 49 of a vertically arranged spring plunger 50 which, as clearly shown in Figs. 1 and 8, is seated in a depression 51 in a block 52 secured by screws 53 to the front of the bracket 37.

A coiled spring 54 is housed in the depression 51 and surrounds the plunger 50, the head of which contacting with the extensions 45 and 47 maintains them normally horizontal and in the position shown in Fig. 1.

It will be observed that the members or key levers 39 and 40 are adapted to act oppositely on the arm 32 to move it lengthwise to and fro; and the construction is such that the plunger 50 maintains the extensions 45 and 47 and the parts controlled thereby in equilibrium. If the operator depresses the finger piece 46, as shown in Fig. 3, the spring plunger 50 will be forced downward and the teeth 43 and 34 will coöperate to draw the arm 32 forward. This forward movement of the arm 32 acts to swing the arm 31 forward, causing the detent roll 24, acting on the ratchet wheel 10, to turn the platen backward in the direction of the arrow in Fig. 3. The parts are so proportioned and adjusted that when the limit of movement is reached, as determined by the contact of the plunger head 49 with the block 52, the platen will have been turned an angular dis-

tance equal to that between the dotted lines *a* and *b* in Fig. 3 and indicated by the reference character *c*. Prior to the turning movement aforesaid, the writing or printing line was where the dotted line *a* intersects the 70 surface of the platen; and as a result of the turning movement the writing will now take place where the dotted line *b* intersects the surface of the platen which is a fractional line space distance above the regular 75 writing line *a*. Consequently exponents or other characters may be written a fractional line spacing distance above the regular line of writing, these characters being termed 80 "superscripts." If a considerable number 85 of these superscripts are to be written, the platen may be locked in the abnormal position shown in Fig. 3 by devices comprising a hook or latch 55 pivoted on the screw pivot 41 outside the bracket 37. Said hook is provided with a finger piece 56 by which it may be swung rearward and downward from the normal position, indicated in Fig. 2 and in full lines in Fig. 3, where it rests against a stop pin 55^a. Fig. 3 shows by dotted lines 90 the hook operatively engaged with a pin 57 projecting laterally from the arm 32, the hook thereby preventing the return of the arm 32 and connected parts to normal position. Unless the hook or latch 55 is used, 95 the platen will remain in abnormal position only so long as the key 46 is maintained depressed by the operator. It will be observed that when the key 46 is being depressed the key 48 rises idly, due to the fact that the 100 rack 35, moving forward, acts on the teeth 44, swinging the extension 47 upward. When the operator releases the key 46 the plunger 50 will rise, forcing the extension 45 upward and the arm 32 rearward and restoring the platen, through the action of the detent 24 on the ratchet wheel 10. The upward movement of the extension 45 will continue until the plunger 50 is engaged by the descending extension 47 which will be when 110 the extensions 45 and 47 are about horizontal, as in Fig. 1. Thus the opposing actions of the members 39 and 40 are balanced, and the arm 32 controlled by said members is maintained in equilibrium, as is also the supporting member 27 and detent 24. When the key 48 is depressed, swinging the member 40 downward, the reverse action takes place, that is, the arm 32 is moved rearward through the action of the gear teeth 44 on the rack teeth 35 and the member 39 rises idly. The rearward movement of the arm 32, acting on the block or detent carrier 27, forces said block to swing rearward with the arm 31. Consequently the detent 24 is 125 swung rearward, and acting on the teeth of the ratchet wheel 10, causes the platen 8 to turn through a fractional line distance in the direction of the arrow in Fig. 4. The distance through which the platen is turned 130

is indicated by the reference character *d* and is the distance between the dotted lines *a* and *e*, *a* representing the normal or original writing or printing line and *e* the abnormal printing line below the line *a*. The result is that if the key 48 be held depressed either by the finger of the operator (or by turning the hook 55 forward as shown by dotted lines in Fig. 4 to act against the forward side of the pin 57), the characters printed through operation of the usual type bars will be in the nature of "subscripts" written below the line *a*. On releasing the key 48 the member 40 will swing upward until the head 49 of the plunger 50 meets the descending member 39 when the parts will be arrested and held in equilibrium in the normal position shown in Fig. 1.

Preferably the keys 46 and 48 are provided with suitable indicating marks, as in Fig. 2, where the key 46 is marked "Sup" which stands for "superscript", and the key 48 is marked "Sub" for "subscript."

It will be seen that by my present invention I have provided a simple auxiliary line shifting mechanism operative independently of the regular line spacing mechanism; that this auxiliary mechanism is conveniently controlled by a plurality of keys arranged at and operative from the front of the platen carriage; that one of these keys, when actuated, operates to shift the line of print or writing a predetermined distance above the normal line, while the other key shifts the line of print a predetermined distance below the normal line; and that these shifting are effected through a detent device which cooperates with the usual ratchet wheel, said detent device, its support and the connections to the keys being maintained in equilibrium in a central position by spring means and movable from said position in either of two directions.

Various changes may be made without departing from the spirit of my invention.

What I claim as new and desire to secure by Letters Patent, is:—

1. In a typewriting machine, the combination with a platen carriage, a platen and a line spacing wheel connected thereto, of line spacing mechanism, a detent, and devices controlled by a plurality of keys for bodily moving said detent in two directions whereby said line spacing wheel and platen may be turned a fractional line space distance either forward or backward at will.

2. In a typewriting machine, the combination with a platen carriage, a platen and a line spacing wheel connected thereto, of line spacing mechanism, a detent co-operative with said wheel, and devices controlled by a plurality of keys for moving said detent bodily at will in either of two directions whereby said line spacing wheel and platen may be turned a fractional line space dis-

tance either forward or backward, one key operating to turn the platen forward and the other key to turn it backward.

3. In a typewriting machine, the combination with a platen carriage, a platen and its line spacing wheel, of a detent co-operating with said wheel, a support on which said detent is mounted, and devices controlled by a plurality of keys at the front of the carriage for at will moving said support in either of two directions.

4. In a typewriting machine, the combination with a platen and its line spacing wheel, of a detent, a support on which said detent is yieldingly mounted, a plurality of keys, and connections between said keys and said support, each of said keys being operative to bodily move said support and turn said platen.

5. In a typewriting machine, the combination with a carriage, a platen and its line spacing wheel, of a detent, a swinging support therefor mounted concentrically with said platen, a key lever at the front of the carriage, and connections between said key lever and said support including a bar extending rearward from said key lever and pivotally connected to said support whereby said key lever is operated to swing said support about the axis of the platen as a center, the movement of said support acting through said detent to turn said platen on its axis.

6. In a typewriting machine, the combination with a platen and its line spacing wheel, of a detent, a swinging support therefor mounted concentrically with said platen, a plurality of keys, and connections between said keys and said swinging support, each of said keys being operative to swing said support and said detent and simultaneously to turn said platen, the movement of the platen and the support being co-axial.

7. In a typewriting machine, the combination with a platen and its line spacing wheel, of a detent, a swinging support mounted co-axially with the platen, a member connected to said support, and a plurality of keys connected to said member and each operative to swing said support and turn said platen co-axially therewith, said member being oppositely movable by said keys.

8. In a typewriting machine, the combination with a platen and its line spacing wheel, of a detent, a support for said detent, a plurality of keys, and connections between said keys and said support, each of said keys being operative to bodily move said support and turn said platen, said connections comprising an arm pivotally connected to said support and provided with oppositely disposed racks.

9. In a typewriting machine, the combination with a platen and its line spacing wheel, of a detent, a support for said detent, a plurality of keys, and connections between

1. said keys and said support, each of said keys being operative to bodily move said support and turn said platen, said connections comprising an arm pivotally connected to said support and provided with oppositely disposed racks, and members on which said keys are supported, said members being provided with gear teeth intermeshing with said racks.
2. 10. In a typewriting machine, the combination with a platen and its line spacing wheel, of a detent, a support for said detent, a plurality of keys, and connections between said keys and said support, each of said keys being operative to bodily move said support and turn said platen, said connections comprising pivotally supported members provided with gear teeth, said keys being mounted on said members.
3. 11. In a typewriting machine, the combination with a plate and its line spacing wheel, of a detent, a support for said detent, a plurality of keys, and connections between said keys and said support, each of said keys being operative to bodily move said support and turn said platen, said connections comprising a member pivotally connected to said support and oppositely movable by said keys.
4. 12. In a typewriting machine, the combination with a platen and its line spacing wheel, of a detent, a support for said detent, a plurality of keys, and connections between said keys and said support, each of said keys being operative to bodily move said support and turn said platen, said connections comprising an arm pivotally connected to said support and provided with bifurcated toothed portions, and devices connected to said keys and coöperating with said toothed portions to move said arm in opposite directions.
5. 13. In a typewriting machine, the combination with a platen carriage, a platen and its line spacing wheel, of a detent, a support for said detent, a plurality of keys, and connections between said keys and said support, each of said keys being operative to bodily move said support and turn said platen, said connections comprising an arm pivotally connected to said support and provided with toothed portions, and pivotally mounted toothed members to which said keys are fixed, said members coöperating with said toothed portions to move said arm in opposite directions.
6. 14. In a typewriting machine, the combination of a platen, detent means, means for moving said detent means either forwardly or backwardly at will, said last mentioned means comprising two key-operated devices that are separately operative at different times, one device to move the detent in one direction and the other device to move the detent in the opposite direction, said two devices being simultaneously movable in opposite directions at either movement of said moving means, and means for maintaining said oppositely movable devices in equilibrium.
7. 15. In a typewriting machine, the combination of a platen, detent devices normally operating to maintain the platen in set positions, a plurality of keys operative on said devices to move the platen oppositely at will, and means for maintaining said devices in equilibrium.
8. 16. In a typewriting machine, the combination with a platen and its line spacing wheel, of a yielding detent normally engaged with said line spacing wheel, a support therefor, spring means, and devices connected to said support and controlled by said spring means for maintaining said support in equilibrium so that said detent may yield to permit movement of said line spacing wheel in either direction.
9. 17. In a typewriting machine, the combination with a platen and its line spacing wheel, of a detent, a support therefor, a plurality of key levers connected to said support, and spring means operative on said key levers for maintaining said support in equilibrium.
10. 18. In a typewriting machine, the combination with a platen and its line spacing wheel, of a detent, a support therefor, a plurality of key levers connected to said support, and a spring plunger operative on said key levers to maintain said support in equilibrium.
11. 19. In a typewriting machine, the combination with a platen and its line spacing wheel, of a detent, an oppositely movable member connected thereto, keys connected to said member, and spring means for maintaining said member in equilibrium.
12. 20. In a typewriting machine, the combination with a platen and its line spacing wheel, of a detent, an oppositely movable member connected thereto, keys connected to said member, and spring means for maintaining said member in equilibrium.
13. 21. In a typewriting machine, the combination with a platen carriage, a platen and its line spacing wheel, of a supporting block, a spring pressed detent mounted on said block and coöperative with said line spacing wheel, an arm pivotally connected to said block and provided with oppositely toothed portions, a plurality of toothed key levers, each key lever coöperating with one of said toothed portions, and a spring device operative on said key levers to maintain said arm in equilibrium.
14. 22. In a typewriting machine, the combination with a platen carriage, a platen and its line spacing wheel, of a supporting block, a spring pressed detent mounted on said

block and coöperative with said line spacing wheel, an arm pivotally connected to said block and provided with oppositely toothed portions, a bracket on said carriage, a plurality of toothed key levers pivoted to said bracket and each engaging with one of said toothed portions, and spring means operative on said key levers.

23. In a typewriting machine, the combination with a platen and its line spacing wheel, of a detent, a support therefor, a plurality of key levers connected to said support, a spring plunger operative on said key levers to maintain said support in equilibrium, and locking devices operative to maintain said detent in abnormal position after actuation by either of said key levers.

24. In a typewriting machine, the combination with a platen and its line spacing wheel, of a detent, a support on which said detent is spring mounted, a plurality of keys, connections between said keys and said

support, each of said keys being operative to bodily move said support and turn said platen to an abnormal position, and latching devices operative to maintain said platen in abnormal position to which it may be turned.

25. In a typewriting machine, the combination of a platen, a ratchet wheel, a detent, a swinging carrier therefor, a key lever provided with teeth, and an arm intermediate the swinging carrier and the key lever pivotally connected to the carrier at its rear end and at its forward end having a rack in engagement with the teeth on said key lever.

Signed at the borough of Manhattan, city of New York, in the county of New York and State of New York, this 19th day of August, A. D. 1912.

CLIO B. YAW.
